UNITED STATES PATENT OFFICE.

JOSEPH GROSS, OF CHICAGO, ILLINOIS.

SAD-IRON.

1,106,649.

Specification of Letters Patent. Patented Aug. 11, 1914.

Application filed May 16, 1913. Serial No. 767,955.

To all whom it may concern:

Be it known that I, JOSEPH GROSS, a citizen of the United States, residing in Chicago, in the county of Cook and State of Illinois, have invented certain new and useful Improvements in Sad-Irons, of which the following is a specification.

My invention relates to sad-irons and has for its primary object the provision of an improved sad-iron which shall have means for being heated both by electricity and flame.

With the above and other objects in view this invention consists substantially in the combination, arrangement, and construction 15 of parts all as hereinafter described, illustrated in the accompanying drawings, which form a part of this specification and show the preferred embodiment of my invention, and more particularly set forth in the sub- 20 joined claims.

In the drawings: Figure 1 is a top plan view of my invention with portions broken away and showing in detached position an electrical plug adapted for coöperation 25 therewith. Fig. 2 is a view of my invention partly in vertical longitudinal section and partly in side elevation. Fig. 3 is a vertical transverse section of my invention taken on the line 3—3 of Fig. 2 and looking in the 30 direction indicated by the arrows. Fig. 4 is a rear end elevation of my invention with a portion of a tube broken away.

In the use of the ordinary sad-iron it frequently happens that the source of supply of 35 heat fails, causing the iron to become cold and unfit for use.

One of the objects of my invention is to obviate such a disadvantage by providing an iron having means for being heated by 40 electricity and flame. To that end I provide a sad-iron which in the preferred embodiment of my invention has two interchangeable surfaces, one heated by electricity and the other by flame, the iron being pivoted at 45 its ends in a suitable hanger and provided with a set-screw for holding the iron in either of its adjusted positions.

Reference numeral 10 indicates a hanger for my improved iron of any convenient 50 form, provided with a heat non-conducting handle 11. Horizontally pivoted at its end in the hanger 10 is an ironing element having two ironing surfaces 12 and 13, the surface 12 being heated by means of an electric- 55 cal element 14 adjacently disposed, and the

surface 13 being heated by means of a gas burner 15 adjacently disposed. The ironing element is apertured preferably at its rear end at points equidistant from its pivotal connection with the hanger 10, as at 16, for 60 engagement with a set-screw 17 which passes through a threaded aperture provided in the hanger 10. If the operator be using the surface 12 of the iron, which is electrically heated, and if during such use the supply of electricity fails, he loosens the set-screw 17 and oscillates the ironing element in the hanger 10 a half revolution or until the surface 13 has taken the place at first occupied by the surface 12. He then lights 70 the burner 15 thereby heating the surface 13 and rendering the iron again ready for use. Preferably the burner 15 is in the form of the well known Bunsen burner, having an outward extension 18 upturned for convenience in operation, provided with the well known adjustable air inlet aperture 19 and the ordinary nipple 20, for engagement with the end of a flexible tube. The extension 18 is detachably connected to the burner 80 15 as at 21. (See Fig. 2.) Preferably, also, the burner 15 is provided with radial apertures 22 angularly disposed with respect to each other for proper disposition of the flame produced with respect to the ironing 85 surface 13, and also, in the preferred embodiment of my invention, the burner 15 constitutes a pipe which at its inner end is embedded in the nose of the ironing element and at its outer end protrudes through the 90 ironing element and the hanger 10 to form a pivot for engagement with the hanger. The ironing element is provided adjacent the burner 15 with a convenient number of air inlet apertures 23. The forward or nose 95 end of the ironing element is provided with a pivot-screw 24 disposed concentric with the axis of the burner 15 and upon which the forward end of the hanger 10 is pivoted.

The electrical heating element 14 is disposed adjacent the surface 12 and a layer of insulating material 25 prevents contact between the ironing element and the heating element. For the purpose of radiating heat of the electrical heating element 14 toward the ironing surface 12 I provide a layer of asbestos or other similar heat radiating material 26, backed by a plate of sheet-iron or similar substance 27, the asbestos and sheet-iron being secured in place in the ironing 110

element by means of a headed screw 28 which engages a tapped stud 29 protruding within the ironing element.

An electrical socket 30 is provided, preferably in the rear vertical surface of the ironing element, for engagement with the points 31 of an electrical plug 32, for the purpose of conveying electricity to the heating element 14. In the preferred form of my 10 invention the ironing element is composed of two separable members, one bearing the electrical element 14 and having the electrically heated ironing surface 12, and the other bearing the burner 15 and having the flame 15 heated ironing surface 13, these two members being secured together by means of shouldered lugs 33 formed upon the electrically heated member and secured to the flame heated member by means of flat head 20 screws 34. The two members of the ironing elements preferably contact at their ends as shown most clearly in Fig. 2 and the sides of the gas heated member are cut away as at 25 (see Figs. 2 and 3) to provide additional intake for air for the flame used.

In the operation of my invention the ironing element may be set to cause the electrically heated surface 12 to be in position for use, following which the plug 32 may be 30 inserted in the socket 30 and the electrical element 14 thereby heated, or if the electricity fails and it is desired to heat the ironing element by flame the ironing element may be reversed into the position shown in 35 drawings, the gas tube connected to the nipple 20, the burner 15 lighted, and the iron used in that position. When the electrically heated ironing surface 12 is in use it is found preferable to disconnect the 40 tension 18 from the burner 15 and vice versa when the flame heated surface 13 is in use it is found preferable to withdraw the plug 32 from the socket 30.

It will be noted that in operation the hand 45 of the operator grasping the handle 1f is protected from the heat radiating from the lowermost heating surface by the interposition of the uppermost heating element between his hand and the lowermost heating 50 element.

In the accompanying drawings and in the foregoing description is set forth the preferred embodiment of my invention, but it is obvious that one skilled in the art may make 55 modifications thereof without departing from the spirit of the invention.

I claim:

1. The combination of a sad-iron having two ironing surfaces, an electrical heating 60 element embodied in the iron, and a flame heating element embodied in the iron, said iron being reversible to place either of the ironing surfaces in operative position.

2. The combination of a sad-iron having 65 two ironing surfaces, an electrical heating

element embodied in the iron for heating one of the ironing surfaces, and a flame heating element embodied in the iron for heating the other ironing surface, said iron being reversible to place either of the ironing surfaces in operative position. 70

3. The combination with a hanger, of a sad-iron pivoted therein, said sad iron having two ironing surfaces and being reversible in the hanger to place either ironing 75 surface in operative position, and heating means of different varieties for the respective ironing surfaces.

4. The combination with a hanger, of a sad-iron pivoted therein, said sad-iron having two ironing surfaces and being reversible in the hanger to place either ironing surface in operative position, an electrical heating element embodied in the iron for heating one of the ironing surfaces, and a flame heating element embodied in the iron 80 for heating the other ironing surface. 85

5. The combination with a hanger, of a sad-iron pivoted therein, said sad-iron having two ironing surfaces and being reversible in the hanger to place either ironing surface in operative position, an electrical heating element embodied in the iron for heating one of the ironing surfaces, a flame heating element embodied in the iron for heating the other ironing surface, and means 90 for locking the iron in the hanger in either 95 of its positions.

6. The combination with a handled hanger, of a sad-iron pivoted therein, said 100 sad-iron having two ironing surfaces and being reversible in the hanger to place either ironing surface in operative position and to cause the ironing surface not in operative position to be interposed between the ironing surface which is in operative position and the handle, and heating means of different varieties for the respective ironing 105 surfaces.

7. The combination with a handled hanger, of a sad-iron pivoted therein, said 110 sad-iron having two ironing surfaces and being reversible in the hanger to place either ironing surface in operative position, and to cause the ironing surface not in operative position to be interposed between the ironing surface which is in operative position and the handle, electrical heating means embodied in the iron, and flame heating 115 means embodied in the iron. 120

8. The combination with a handled hanger, of a sad-iron pivoted therein, said 125 sad-iron having two ironing surfaces and being reversible in the hanger to place either ironing surface in operative position and to cause the ironing surface not in operative position to be interposed between the ironing surface which is in operative position and the handle, electrical heating means embodied in the iron, flame heating means 130

embodied in the iron, and means for locking the hanger in either of its positions.

9. The combination with a handled hanger, of a sad-iron horizontally pivoted therein at its ends, said iron including a flame heated ironing element and an electrically heated ironing element superposed upon the flame heated ironing element in inverted position and secured thereto, said 10 sad-iron being reversible in the hanger to cause either ironing element to assume an operative position and to cause the other ironing element to be interposed between the ironing element which is in operative 15 position and the handle, and means for locking the sad-iron in the hanger in either of its positions.
10. The combination with a handled hanger; of a sad-iron pivoted therein; said 20 iron including a hollow flame heated ironing element having its upper edges cut away intermediate its ends; an electrically heated ironing element superposed in inverted position upon the flame heated ironing element; shouldered lugs protruding from the electrically heated ironing element across the cut away portion of the flame 25 heated ironing element; locking means upon the flame heated ironing element coöperating with the shouldered lugs to secure the two ironing elements together; said sad-iron being reversible in the hanger to cause 30 either ironing element to assume an operative position.
- 35 11. The combination with a hanger, of

a sad-iron pivoted therein, said sad-iron having two ironing surfaces and being reversible in the hanger to place either ironing surface in operative position, an electrical heating element embodied in the iron for 40 heating one of the ironing surfaces, a flame heating element embodied in the iron for heating the other ironing surface, means embodied in the iron for detachably connecting the electrical heating element there- 45 of to a source of electrical supply, and a detachable tube upon the iron for connecting the flame heating element with a source of supply of combustible fluid.

12. The combination of a sad-iron having 50 two unbroken ironing surfaces, an electrical heating element embodied in the iron and positioned adjacent one of the ironing surfaces for heating it, a sheet of heat reflecting material positioned adjacent to the electrical heating element and upon the side opposite the ironing surface which it heats, and a flame heating element embodied in the iron for heating the other ironing surface, said iron being reversible to place 55 either of its ironing surfaces in operative position.

In testimony whereof I have signed my name to this specification, in the presence of two subscribing witnesses, on this 14th day 60 of May, A. D. 1913.

JOSEPH GROSS.
